[57] CLAIM

The ornamental design for a cigarette troche holder, as shown and described.

DESCRIPTION

FIG. 1 is a front perspective view of a combined cigarette and pill dispenser showing my new design;

FIG. 2 is a bottom plan view;

FIG. 3 is a rear elevational view;

FIG. 4 is a top plan view;

FIG. 5 is a view looking from the right of FIG. 2;

FIG. 6 is a view looking from the left of FIG. 2; and

FIG. 7 is a sectional view taken on the line 7—7 of FIG. 2.

The broken lines in FIG. 7 showing cigarettes and pills are for illustrative purposes only.

FIG. 1.

FIG. 2. ↗7

FIG. 5. ↗7
